UNITED STATES PATENT OFFICE.

LAWRENCE E. ROBINSON, DECEASED, BY EDITH A. ROBINSON, ADMINISTRATRIX, OF COFFEYVILLE, KANSAS.

OIL-WELL PACKER.

Application filed August 8, 1921. Serial No. 490,443.

To all whom it may concern:

Be it known that I, EDITH A. ROBINSON, a citizen of the United States, residing at Coffeyville, Montgomery County, Kansas, declare that LAWRENCE E. ROBINSON, deceased, invented certain new and useful Improvements in Oil-Well Packers; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to an oil well packer.

It is the usual practice to line wells with tubular casings of progressively decreasing diameters from the top to the bottom, each 20 casing extending entirely to the top so that near the top of the well there are a number of casing tubes concentric one with the other, the inner tube or casing of smallest diameter being really the only effective casing for the 25 flow of oil from the oil sands to the top of the well.

It has also been common practice to omit the casing from that portion of the well passing through solid or dry foundations at 30 the bottom of the well, but in such instances it becomes necessary to afterwards case off such portions should the foundation develop what is known as a cave. This casing-off is done by means of a packer to which the new 35 casing or liner is attached, the casing and packer being lowered into the well and the packer secured to the lower end of the original casing so that the new casing is suspended therefrom to protect the caved portions of the hole. Heretofore such packers 40 have been let into the well by means of small tubing to which the packer is secured by left hand threads on a letting-in tool so that when the packer is in place, a set of jaws or gripper is relaxed to permit the packer to grip the casing and the letting-in tool unscrewed from the packer and pulled from the well.

It is the principal object of the present 50 invention to provide a packer which may be released from the letting-in tool by a simple vertical movement of the tool, thereby saving considerable time and trouble in installation, and while I have referred to the packer 55 as a cave or liner packer, I do not wish to

be understood as limiting it to such use as it may be used where trip-wall, disc-wall or other packers using slip mechanism may be employed.

The invention consists in certain novel arrangements of parts and combinations of parts, all of which will be specifically described hereinafter, reference being had to the accompanying drawings, in which—

Fig. 1 is a perspective view of a liner or 65 cave packer illustrating the invention.

Fig. 2 is a vertical, longitudinal, sectional view through the same showing the letting-in tool and the locking connection or disc for the packer.

Fig. 3 is an elevational view of the invention passing downwardly through the casing 70 with liner and cave catcher attached.

Fig. 4 is a similar view showing the slips or casing engaging jaws moving into expanding position on the slip carrier or setting reins preparatory to receiving the final expander or cone necessary to force the slips or jaws to the casing.

Fig. 5 is a like view showing the final expander or cone and slips or casing engaging jaws moving into setting position on cone or final expander.

Fig. 6 is a like view showing the slips or casing engaging jaws set in casing and disc 85 in letting-in tool being broken to release the letting-in tool.

Fig. 7 is a view showing packer set and liner supported by packer and the letting-in tool released from the packer showing broken 90 disc parts coming out of well with letting-in tool.

Fig. 8 is a sectional view on the line 8—8 of Fig. 3.

Fig. 9 is a similar view on the line 9—9 of 95 Fig. 3, and

Fig. 10 is an enlarged sectional view through the letting-in tool and the upper end of the expander or cone to illustrate the method of collapsing the locking disc or 100 connection between them.

Referring now to the drawings by numerals of reference:

1 designates the initial casing in the oil well 2 surrounded by the stratified earth and 105 rock as illustrated, the strata designated 3 representing the cap rock located above the oil sands. The reference numeral 4 designates the liner or smaller casing provided with the usual bottom shoe 5 at its lower end, 110

as will be well understood, and fastened to the packer body or tube 6 by a coupling or collar 7, which is threaded so as to screw onto the lower end of the body or tube 6 and to the upper end of the liner 4, as best shown in Fig. 2.

Above the collar 7 is a stop collar 8 adapted to support a loosely mounted collar or ring 9, sleeved over the metallic packer body or tube 6 and having a plurality of upstanding jaw expanding fingers 10 guided in the grooves 11 in the collar or slip rein 12 having a plurality of yielding upstanding reins or fingers 13, which carry segmental slips or jaws 14 arranged about the body or tube 6 to complete the ring, the slips or jaws 14 having undercut teeth 15 to engage the inner surface of the casing 1.

Carried by the ring or collar 12 are bowed springs 16, the portions 17 of which are adapted to frictionally engage the inner surface of the casing 1 to constitute lag springs so as to normally hold the slips and rims or cage formed by the collar or ring 12, the jaws 14 and the yielding arms 13 adjacent to the cone-shaped head or expander 18 forming the upper end of the body or tube 6.

The cone or head 18 is provided internally with an annulus or groove 19, having radial inlet slots 20 and 21 to receive the bolted disc ends 22 and 23 of the disc or lock for fastening the letting-in tool to the cone or head 18. The letting-in tool is shown as comprising a hollow member 24 adapted to be fastened to the tool sub or other tool by a coupling 25. The letting-in tool is provided with oppositely located openings or slots 26 and 27 through which project the disc ends or bolts 22 and 23 pivoted together at 23' and having shoulders 27' and 28 against which abut the respective ends of the complementary disc or bolt members 22 and 23, as shown in Fig. 8, so that when the edges 29 and 30 of the slots 26 and 27 exert pressure against the disc or bolt ends, the disc or lock will be held in operative position to connect the letting-in tool to the cone or head 18. The disc halves are held in place by fragile fastening devices 31 and 32, which may be easily sheared when the bar or rod 35 contacts on downward motion with the locking device or disc above the pivot 23' which may also be fragile enough to be broken when subjected to a severe blow, it being the purpose of the invention to provide means whereby the two halves of the disc 22 and 23 may become separated when subjected to a sharp downward blow from the letting-in tool cross bar 35, as shown in Fig. 10, and will leave the parts in the position shown in Fig. 7, disconnected from the packer and hanging by wires to letting-in tool, the sub and stem, whereby the letting-in tool or other support may be removed from the well.

The disc or locking device may be introduced into the annular groove 19 through the slots 20 and 21 and then held against displacement except by severing the connection through the medium of the screws 36 and 37 (see Figs. 3, 4 and 8), these being insertable after the locking device consisting of the disc halves or bolts 22 and 23 are in place. Therefore, the disc or bolt members 22 and 23 cannot align with the slots 20 and 21 and become accidentally detached from the cone or head.

After the parts are connected as shown in Fig. 1 with the liner secured to the cave or liner packer, the packer and liner may be lowered into the well through the casing 1, the bowed portions 17 of the springs 16 frictionally engaging the inner surface of the casing to serve as lag springs to maintain the slips and reins or cage consisting of the ring 12 and its appurtenances in the position shown in Fig. 1. The depth of the casing 1 having been previously measured, the packer and liner will be lowered the proper distance. Then there will be a slight upward movement imparted to the packer body or tube 6 and, of course, to the liner 4. Since the slip reins or cage having the slips or jaws 14 will be held stationary, the free ends 10' of the wedge fingers 10 will enter the flared portion 14' of the slips or jaws and spread them apart enough to cause them to overlap the cone shoulder 18' on the cone or head 18. Then the packer body or tube 6 will be lowered, permitting the wedge-shaped cone or head 18 to further expand the jaws to cause them to bind and impinge against the inner surface of the casing 1 and thereby set the packer and the liner with respect thereto, the biting of the case hardened teeth into the metal of the inner wall of the casing 1 being sufficient to form a secure attachment.

If at the time the cone or final expander or head 18 is lowered into the ring formed by the slips or jaws 14, the letting-in tool is permitted to exert a sharp downward blow against the locking connection or disc consisting of the halves of the disc or bolts 22 and 23, the pivot 23' and the pins 31 and 32 will be sheared or broken so that the lock will be rendered ineffective, as shown in Figs. 6 and 10, and the letting-in tool may be drawn out, as shown in Fig. 7, leaving the liner or cave packer locked within the casing with liner suspended therefrom. The disc halves 22 and 23 need not be lost, however, for they can be secured to the letting-in tool by the flexible connections 38 and 39.

In order to stop cavings from falling into the oil sand, a frill or cave catcher 40 may be supported by the shoe 5 on the liner 4 to constitute a baffle whereby dirt and rock dislodged above the same may be obstructed and prevented from falling into the oil sands.

as such particles tend to obstruct the passage of the oil through the casing and pumping equipment.

It is to be noted that the frill or cave catcher has an expanding diameter of fingers approximately equal to that of the oil well so that it will properly perform the service for which it is intended.

It is also to be noted that with the liner 10 or cave packer secured to the lower portion of the original casing in the manner described, the necessity for running the liner up to the top of the well will be eliminated and while the cost of the liner packer or connection 15 is considerable, it will be infinitely less than the cost of the extra casing so that there will be a considerable saving in lining the well.

It is observed that the ring 9 is relatively 20 loose on the packer body or tube 6 so that as soon as the arms 10 have moved the slips or jaws 14 outwardly and the body or tube 6 is dropped, the slip carrier or ring 9 of the setting reins will withdraw the arms 25 or fingers 10 so that they will not be in the way of the conical expanding head or cone 18, which drives the slips or jaws 14 home in their engagement with the inner face of the casing 1. It will, therefore, be apparent 30 that the device can be readily set in position in an expeditious and convenient manner.

I claim:

1. In a device of the class described, a body, a casing engaging member loosely 35 mounted on the body and having expanding slips, means for partly separating the slips to expanding position, and means on the body for further expanding the slips into casing-engaging position so that the packer will be secured to the casing in which it is 40 located by vertical motion of the casing controlled from the top of the well by connecting casing.

2. In a device of the class described, a body, an expanding casing-engaging member 45 loosely mounted on the body, lag springs connected to the casing-engaging member having free longitudinal movement on the body for partly expanding the casing-engaging member, and means on the body for finally expanding the casing 50 engaging member by the weight of the body and tools connecting.

3. In a device of the class described, a body having a conical head at one end, a ring loosely mounted on the body and having upstanding arms, slips carried by the arms, another ring having movement independent of the first named ring, and fingers 60 on the second mentioned ring insertable between the slips and the body for moving the slips outwardly beyond the edge of the conical head whereby the conical head may drop into the space confined by the slips to expand 65 them against a surrounding casing by verti-

cal movement of the body and tools connecting.

4. In a device of the class described, a body having a conical head at one end, means for securing a liner section to the other end, a ring loosely mounted on the body, upstanding yielding arms carried by the ring, lag springs carried by the ring and having their free ends bearing against the upstanding arms, the lag springs being 70 bowed to frictionally engage the inner surface of the wall of the well, a second slidably ring on the body, and upstanding fingers on the second ring insertable between the jaw members and the body to force them outwardly to enlarge the opening surrounded by them so that the conical head may be introduced between the jaw members to expand 75 them into casing-engaging position.

5. In a device of the class described, a body having an expander at one end and means for attachment to a liner at the other, a ring having guides loosely mounted on the body, jaws yieldingly connected to said ring, lag springs carried by the ring, a second ring having free independent movement with respect to the body, and jaw-expanding fingers carried by the second 90 mentioned ring and projecting through the guides in the first named ring, said fingers 95 being insertable between the jaw members and the body to move them outwardly so that the expander may be received by the jaws to permit it to expand the jaws into casing-engaging position.

6. In a device of the class described, a body, a circular jaw member carried by the body having outwardly movable jaws, a head on the body for expanding the jaw member, means for holding the jaw member rigid while the body moves, a letting-in tool, and a releasable connection between the letting-in tool and the body by vertical movement of the letting-in tool and tools connecting.

7. In a device of the class described, a body having a cone-shaped upper portion provided with a groove, a circular jaw member carried by the body having outwardly movable jaws, a head on the body for expanding the jaw member, means for holding the jaw member rigid while the body moves, a letting-in tool, and a releasable connection between the letting-in tool and the body, said releasable connection comprising aligning disc members and disruptible means for connecting them together, the ends of the aligning members being insertable in the groove in the cone-shaped portion.

8. In a device of the class described, a body, a cone at the upper end of the body having a groove, a circular jaw member carried by the body having outwardly movable jaws, a head on the body for expanding the jaw 130

member, means for holding the jaw member rigid while the body moves, a letting-in tool, and a releasable connection between the letting-in tool and the body, said connection comprising two pivoted members having offset shoulders for engaging ends of complementary members, and disruptible connecting means for said members adapted to break under the downward action of the letting-in tool, the connecting means extending through the letting-in tool and having its ends received in the groove in the cone of the body.

9. The combination with a packer comprising a body having a cone-shaped upper end provided with a groove, and a letting-in tool, of means for temporarily securing the letting-in tool to the body portion of the packer, said means comprising two bars fastened together by disruptible fastening means and extending through elongated slots in the letting-in tool and into the groove in the cone-shaped portion of the body portion of the packer.

10. The combination with a packer and a

letting-in tool, of means for temporarily securing the letting-in tool to the packer, said means comprising a disruptible connection between the letting-in tool and the packer.

30

11. The combination with a packer and a letting-in tool, of means for temporarily securing the letting-in tool to the packer, and means for disrupting the securing means upon vertical movement of the letting-in tool independent of the packer.

12. The combination with a packer and a letting-in tool, of means for normally suspending the packer from the letting-in tool, and means for permitting independent downward movement of the letting-in tool when the packer is set so as to disrupt the packer suspending means to permit the letting-in tool to be withdrawn therefrom.

In testimony whereof I affix my signature.

EDITH A. ROBINSON,
